UNITED STATES PATENT OFFICE.

GEORGE R. CLARKE, OF MONTELL, TEXAS, ASSIGNOR TO HENRY H. TURNER AND ALBERT TURNER, OF DANBURY, CONNECTICUT.

POUNCING-MACHINE.

SPECIFICATION forming part of Letters Patent No. 602,978, dated April 26, 1898.

Application filed December 17, 1896. Renewed October 1, 1897. Serial No. 653,746. (No model.)

To all whom it may concern:

Be it known that I, GEORGE R. CLARKE, a citizen of the United States, residing at Montell, Uvalde county, Texas, have invented certain new and useful Improvements in Pounding-Machines, of which the following is a specification.

This invention relates generally to a machine for pouncing the crowns of hats, and specifically to certain improvements on the machine embodied in my application, Serial No. 577,650, filed February 1, 1896, and now pending.

The features of improvement will be hereinafter described and carefully distinguished from the old features of the machine as shown in the said pending application.

In the accompanying drawings an embodiment of the improved machine is illustrated.

Figure 1 is a side elevation of the machine as it appears at the termination of the pouncing operation, the base of the pedestal being in section. As the operator stands at the right in Fig. 1 and facing the machine this view shows the left-hand side thereof. Fig. 2 is a front elevation of the upper part of the machine, on a larger scale than Fig. 1, showing the parts in the position they occupy at the beginning of the pouncing operation; and Fig. 3 is a side elevation as seen from the right in Fig. 2. These views, Figs. 2 and 3, include the novel features of this invention. Fig. 4 is a face view of the pouncing-pad detached.

I will first briefly explain the general construction and operation of the machine, as more fully set forth in the above-mentioned pending application, and then describe the novel features.

On a hollow pedestal or frame 1 is mounted a head 2, which is carried by an upright hollow shaft 3 in the pedestal, and during the pouncing operation said head is turned slowly around through about a quarter-revolution. When the operation is completed, the driving mechanism is automatically thrown out of gear, (as here shown by shifting a belt,) and the head may be then unlocked or disconnected from its shaft and turned back again to the starting-point. The hat H to be pounced is fitted on a block clutched to a horizontally-

mounted shaft in the head, and this shaft is driven, through intermediate mechanism, from an upright shaft 4, extending through the hollow shaft 3. The hat is thus rotated slowly about its axis at the same time that it is carried about with the head 2. The main driving-shaft 5 in the base of the frame or pedestal drives the shafts 3 and 4 through any suitable gearing. In Fig. 1 this consists of a peculiar differential gear, which is fully described in the said pending application. As the hat H is rotated it is pounced by a pouncing-pad 6, carried by an arm 7 and held up to the hat by a spring in a casing 8 on the pedestal or frame. The pad 6 receives motion in a closed curved path through the medium of a counter-shaft 9 in the frame, driven from the main shaft 5. On the end of the shaft 9 is a crank 9^X, to which the lower end of the arm 7 is coupled, and the said arm has a sliding bearing at 10 in a frame 11, hinged to the pedestal 1. All of this is clearly illustrated and described in the said pending application.

I will now describe with more particularity the means employed for giving to the hat what is called an "oval" motion about its axis, premising that as a hat-crown is elliptic or oval in cross-section and the pad is held up to it by a yielding spring-pressure it is desirable that the center of rotation of the hat shall be moved to and fro during the rotation toward and from the pouncing-pad in order to compensate for the elliptical form of the hat-crown, and thus avoid variable pressure of the pad on the hat during its rotation.

On the upper end of the shaft 4 is fixed a bevel-wheel 12, which gears with a bevel-pinion 12^X, fixed on a counter-shaft 13, mounted in bearings in the head 2 perpendicular to the shaft 4. On the shaft 13 is fixed a gear-wheel 14, which gears with a similar wheel 14^X, of twice its size, fixed on the shaft 15, which carries the hat H and which is relatively mounted in a bearing-piece 16, mounted loosely on the shaft 13, at its foot, and adapted to swing or oscillate about the axis of said shaft 13 as a center. The shaft 15 is substantially parallel with the shaft 13, and the oscillation of the bearing-piece 16 does

not disturb the intermeshing of the teeth on the wheels 14 and 14^x. On the head 2 is a suitable bracket 17, to which is secured a fulcrum-arm 18, and to the outer end of this arm is coupled a longitudinally-slotted lever 19 by means of a fulcrum-bolt 20, the construction being such that the lever may be fulcrumed on the arm 18 at any point along the slot. An arm or connecting-rod 21 is coupled at and to the upper arm of the lever 19, and in the other end it has an eye which loosely embraces the boss of the wheel 14^x. Another connecting-rod 22 is coupled at one end to the lower arm 15 of the lever 19, and in the other end has an eye which embraces an eccentric 23, formed on the boss of the wheel 14. The effect of the above-described mechanism is to rotate the shaft 15 and at the same time impart to it, through the eccentric 23, rocking lever 19, and rods 21 and 22, a motion toward and from the pouncing-pad, this oscillation being effected twice during each rotation of the hat. The extent of this oscillation may be varied at will by loosening the fulcrum-bolt 20 and moving the lever 19 up or down in order to vary the length of its arms, and the construction enables this to be done quickly and conveniently without disturbing or dismantling the machine. Indeed it is feasible to do it while the machine is in operation. Of course it will be understood that the forming of the eccentric 23 integral with the boss of the wheel 14, the mounting of the bearing-piece 16 directly on the counter-shaft 13, and other minor details of the construction are merely matters of choice and need not be strictly followed in carrying out the invention in practice.

In order that the pouncing-pad may adjust itself the better to the surface of the hat, especially in passing about an abrupt curve where the side of the hat-crown joins the top thereof, the pad is swiveled in the line of its longitudinal axis, as will now be described.

The pad 6 is made by preference of rubber and faced with fine sandpaper suitable for pouncing. The pad proper is provided with metal end pieces 6^x, to which it is removably secured by a screw and thumb-nut 6^a, so that it may be readily removed and replaced. On each end piece 6^x, in line with the longitudinal axis of the pad, is a collared journal 6^b, which finds a bearing in a suitable pad-support 7^x on the arm 7. The journals 6^b permit the pad to turn freely about its longitudinal axis when the exigencies of the case, as stated above, require it to do so. To avoid marking the hat in the pouncing, it is desirable that the pad shall be free to adapt itself to the surface to be pounced at all times.

When the pouncing operation is completed, the motion of the machine is stopped by the automatic shifting of the driving-belt, and at the same time the pad is pushed quickly away from the hat and back to the position seen in

Fig. 1, where it is held until the pounced hat is removed and replaced by another and the head 2 turned back to the starting-point.

In the before-mentioned pending application the belt-shifting device is shown, the same comprising the elbow-lever 24, coupled by a link 25 to the shifting-spring 26, and the toggle 27, which holds the lever 24 when set. It also shows the means for breaking the knuckle of the toggle upward at the termination of the pouncing operation, such means comprising a pin 28, carried by the head 2, adapted to act through a suitable lever 29 to "break" the toggle. A lever 30, fulcrumed on the pedestal back of the toggle, is coupled at its lower end by a link 30^a to the hinged frame 11, and at its upper end it has a pin 30^x, which engages the lever 24. Fig. 3 shows the position of the parts at the moment before the knuckle of the toggle is broken upward. When this takes place, the quick movement of the upper end of the lever 24 swings the lever 30 over and pushes the frame 11 back. This frame carries back the pouncing-pad, the arm of the latter being hinged at the point where it is coupled to the crank 9^x.

In Fig. 3 I have only shown a part of the teeth on the wheels 14 and 14^x, and in Fig. 2 a part of the head 2 is represented in section, as is also the boss of the wheel 14 and the eccentric 23. The nut and washer on the outer end of the shaft 13, to keep the connecting rod, yoke, or eye in place on the eccentric, is omitted from Fig. 3, so that the eccentric may be seen. Of course an ordinary crank on the shaft 13 will serve in lieu of an eccentric. It will be understood that I do not herein claim the driving mechanism shown in Fig. 1 at the base of the machine, nor do I limit myself thereto. Any known form of mechanism may be employed for driving the several shafts 3, 4, 5, and 9.

Having thus described my invention, I claim—

1. In a pouncing-machine, the combination with the head 2 and shaft 4, of mechanism for imparting to the hat an oval or elliptic rotary movement, said mechanism comprising the rocking bearing-piece 16, mounted on the head, the shaft 15 for carrying the hat mounted in said bearing-piece, gearing between the shafts 4 and 15, whereby the former drives the latter, and mechanism substantially as described for imparting an oscillatory movement to the said bearing-piece 16 during each half-revolution of the shaft 15, substantially as set forth.

2. In a pouncing-machine, the combination with the head 2, the rocking bearing-piece 16, mounted thereon, and the shaft 15, rotatively mounted in the latter, of the rotating shaft 13, mounted in the head parallel with the shaft 15, gearing between the said shafts 13 and 15, whereby the former drives the latter, an eccentric on the shaft 13, the fixed fulcrum-arm 18 on the head, the lever 19, fulcrumed adjustably on the arm 18, a connecting-rod

which couples the upper arm of the lever 19 with the shaft 15, and a connecting-rod coupling the said eccentric with the lower arm of said lever, substantially as set forth.

- 5 3. In a pouncing-machine, the combination with the head 2, and the rotating shaft 13, mounted rotatively in bearings therein, of the rocking bearing-piece 16, mounted at its foot as shown, the shaft 15, which carries the hat, mounted rotatively in said bearing-piece and parallel with the shaft 13, the gear-wheels 14 and 14^x, on the respective shafts 13 and 15, mechanism for rotating the shaft 13 and through it driving the shaft 15, a lever 19, fulcrumed on the head, an eccentric on the shaft 13, a connecting-rod coupling said eccentric with one arm of the lever 19, and a connecting-rod coupling the other arm of said

lever with the shaft 15, substantially as set forth. 20

4. In a pouncing-machine, the combination with the arm which carries the pouncing-pad, and mechanism for imparting motion to said arm and pad, of a flexible pad coupled at its ends to the arm and under longitudinal tension, said pad being provided with collared journals at both of its points of attachment whereby it is adapted to turn about its longitudinal axis, as set forth. 25

In witness whereof I have hereunto signed my name in the presence of two subscribing witnesses.

GEORGE R. CLARKE.
